CLAIM

The ornamental design for a bowl stand, as shown and described.

DESCRIPTION

FIG. 1 is a perspective view of a bowl stand depicting a first embodiment of a new design;

FIG. 2 is a front view thereof;

FIG. 3 is a rear view thereof;

FIG. 4 is a side view thereof, the opposite side being identical thereto;

FIG. 5 is a top view thereof;

FIG. 6 is a bottom view thereof;

FIG. 7 is a perspective view of the bowl stand according to a second embodiment;

FIG. 8 is a side view thereof, the opposite side view being identical thereto;

FIG. 9 is a rear view thereof;

FIG. 10 is a front view thereof;

FIG. 11 is a top view thereof; and,

FIG. 12 is a bottom view thereof.

The broken lines depict unclaimed portions of the bowl stand and form no part of the claimed design.

1 Claim, 9 Drawing Sheets
